FIG. 4

FIG. 6

FIG. 1 is a perspective view of a teaspoon showing our new design.

FIG. 2 is a side elevational view thereof.

FIG. 3 is a top view thereof.

FIG. 4 is a bottom view thereof.

FIG. 5 is an enlarged cross-sectional view taken on line 5—5 of FIG. 2.

FIG. 6 is a cross-sectional view taken on line 6—6 of FIG. 3.

The characteristic features of our design reside in the elongate ridge which extends along the entire length of the upper surface of the handle portion through the throat area downwardly well into the functional spoon end and in the downwardly extending edge portions which also extend the entire length of bottom surface of the handle portion through the throat area well into the functional spoon end.

We claim:

The ornamental design for a teaspoon, as shown and described.
